OIL BURNER

Mark Strosk, Washington, D. C.

Application December 15, 1938, Serial No. 245,886

4 Claims. (Cl. 299—120)

This invention relates to oil burners and particularly to an improved burner which may be used in steam producing boilers on steamships, and elsewhere, an object being to provide a construction which is simple and very effective to secure a desired whirling spray.

Another object of the invention is to provide an oil burner for boilers and the like, wherein means are provided to produce a whirling spray without any moving parts and with a minimum path for the passage of oil from the supply pipe to the nozzle opening.

An additional object is to provide an oil burner formed of a minimum number of parts wherein the structure is so formed that the part carrying the nozzle opening may be varied and the remaining parts adjusted to vary the flow of oil according to the size of the nozzle opening.

In the accompanying drawing—

Fig. 1 is a vertical sectional view through an oil burner disclosing an embodiment of the invention, the section being taken along line 1—1 of Fig. 6;

Fig. 2 is a top plan view of the structure shown in Fig. 1;

Fig. 3 is a vertical sectional view through the nozzle or clamping nut shown in Fig. 1;

Fig. 4 is a plan view of the nozzle block shown in Fig. 1;

Fig. 5 is a sectional view through Fig. 4 approximately on the line 5—5;

Fig. 6 is a sectional view through Fig. 1 approximately on the line 6—6;

Fig. 7 is a sectional view through Fig. 6 approximately on the line 7—7;

Fig. 8 is a view similar to Fig. 7 but showing a different position of the nozzle block;

Fig. 9 is a view similar to Fig. 1 but showing a modified form of the invention;

Fig. 10 is a view similar to Fig. 9 but showing a nozzle block in a different position.

Referring to the accompanying drawing by numerals, 1 indicates an oil supply pipe which may supply oil under desired pressure from any suitable source. Connected to this pipe is the burner which consists principally of a burner body 2 and a nozzle nut 3. From an examination of Fig. 1 and also of Fig. 9, it will be seen that the complete burner is made from a minimum number of parts. In Fig. 1 there are shown three parts while in Fig. 9 there will be three parts when the burner is complete by the addition of a nozzle nut 3.

The body 2 is provided with a square or hexagonal end 4, whereby it may be readily secured

on to pipe 1. Extending forwardly from the part 4 is an exteriorly threaded portion 5 on which the interiorly threaded clamping nut 3 is screwed until the surface or shoulder 6 presses against the surface 13 of block 12.

In the form of the invention shown in Fig. 1, a separate oil-deflecting cap 7 is forced into the end of the threaded section 5 until the upper surface of cap 7 is flush with the upper end of section 5. Cap 7 is really a round disk pressed into the position shown in Fig. 1 and held therein by friction. This cap is provided with four tangentially and diagonally arranged passageways or apertures 8 which are preferably disposed at an angle of approximately twenty degrees with a plane perpendicular to the axis of the burner, as shown in Fig. 6.

As the oil under pressure from pipe 1 is forced against the inner surface of cap 7, some of the oil will pass through the various passageways or jet openings 8 in different directions, whereby the oil is caused to whirl in the whirling chamber 9. From this chamber the oil in a whirling state is projected outwardly through the nozzle opening 10. The distance which the sprayed oil will travel depends upon the pressure used. However, as the oil moves away from the opening 10, it will whirl and move in a substantially cone shape as it burns so that there will be little or no loss.

By the arrangement just described, as shown in Fig. 1, it will be observed that there is ample space for the oil except in the passageways 8 and opening 10 where the oil is restricted. As these passageways are very short, the burner will function for long periods of time without requiring cleaning. Each of the passageways 8 is of the same size or slightly larger than the opening 10, whereby an appreciable pressure will be produced in the whirling chamber 9 before the oil passes out the opening 10 in a fine spray.

As illustrated particularly in Figs. 7 and 8, the block 12 may be changed from time to time as desired so as to vary the opening 10. When the structure is arranged as shown in Fig. 7, the passageways 8 are free but whenever desired the block 12 could be removed and another block substituted having a different diameter of whirling chamber 9. As shown in Fig. 8, the block 12 is arranged to overlap and thereby partly shut off each of the passageways 8. In all forms of the invention it will be observed that the nozzle block 12 is provided with the central opening 10 which may be varied in size as desired and that the block is formed with an annular extension 11 which fits into the aperture 11 of the nut 3. The

aperture 10 is central of the nut 3 as well as central of the block 12 and the passage in the burner member 2. When the nut 3 is screwed down tight the surface 6 will press against the 5 surface or shoulder 13 and clamp the lower surface of the block 12 against the shoulder 13 whether the whirling chamber 9 is large or small. As shown in Fig. 7, the whirling chamber is large, while in Fig. 8 it is small, but in both instances 10 the outlet 10 is central of the block.

As illustrated in Fig. 9, an oil-deflecting block 17 is made integral with the section 5. Aside from this detail the construction is identical with that shown in Fig. 1 and is adapted to receive 15 a block 12 and clamping nut 3 of the type shown in Fig. 1. When using the construction shown in Fig. 9 with the block 12 and shown in Fig. 5, only three parts are used and these three parts make up the complete burner.

20 By providing a structure formed of few parts and constructed with very short passageways, the burner will not need cleaning except after long use, and when a cleaning operation is desired it may be quickly done as easy access is 25 secured to all the passageways after the nozzle has been unscrewed. It is understood, of course, that the entire burner could be made of various sizes and used for various purposes without departing from the spirit of the invention.

30 I claim:

1. An oil burner of the character described including a burner body having an oil inlet at one end and a plurality of oil outlets at the opposite end, said outlets comprising a plurality 35 of diagonal tangentially arranged passageways at an angle of approximately twenty degrees with a plane perpendicular to the axis of the burner with the discharge ends of the passageways arranged in a circle spaced from a central point, 40 a nozzle block arranged against the end of said burner body, said nozzle block having a central outlet and an uninterrupted open whirling mixing chamber having a flat top and a flat bottom, said top and bottom being arranged parallel, 45 said nozzle block having a shoulder surrounding the same and positioned to overlap somewhat the outlet end of said passageways, said block having an outlet opening which is proportional to the size of the whirling and mixing chamber and 50 the position of said shoulder being arranged so that the outlet opening is of given size and said shoulder overlaps and closes a certain proportion of the discharge ends of said passageways, and means for clamping said nozzle block in functioning position.

55 2. An oil burner including a burner body having an oil inlet at one end and an oil outlet structure at the opposite end, said outlet structure including a plurality of tangentially arranged passageways at an angle of approximately twenty 60 degrees with a plane perpendicular to the axis of the burner with the discharge ends arranged in a circle on the discharge face of said outlet structure, a nozzle block arranged to press against said 65 discharge face, said nozzle block having a dis-

charge opening, said nozzle block and said outlet structure forming an uninterrupted open chamber for receiving the oil passing through said passageways, said chamber and said passageways being arranged so that the oil from the 5 passageways will first move tangentially across said chamber and then merge into a whirling central mass which in turn merges into a single stream passing through said discharge opening and means for securing said nozzle block in position.

3. An oil burner including a burner body having an oil inlet at one end and an oil outlet structure at the opposite end, said outlet structure having a plurality of tangentially arranged passageways at an angle of approximately twenty 15 degrees with a plane perpendicular to the axis of the burner with the discharge ends arranged in a circle at the discharge face of the outlet structure, a nozzle block having in one face a whirling and mixing chamber with the top and bottom parallel and the space between the top and bottom open and uninterrupted and a centrally positioned discharge opening merging into said chamber, said nozzle block being positioned 20 on said outlet structure so that the top surface of the outlet structure forms the bottom wall of said chamber, said passageways being arranged in respect to said chamber so that the oil discharging therefrom will first move tangentially 25 across the peripheral part of the chamber, then merge into a whirling central mass and finally form a single stream passing through said discharge opening and means for securing said nozzle block to said burner body.

30 4. An oil burner including a burner body having an oil inlet at one end and an oil outlet structure at the opposite end, said outlet structure having a plurality of tangentially arranged passageways at an angle of approximately twenty 40 degrees with a plane perpendicular to the axis of the burner with the discharge ends arranged in a circle at the discharge face of the outlet structure, a nozzle block having in one face a whirling and mixing chamber with the top and bottom 45 parallel and the space between the top and bottom open and uninterrupted and a centrally positioned discharge opening merging into said chamber, said nozzle block being positioned on said outlet structure so that the top surface of the outlet structure forms the bottom wall of said 50 chamber and overlaps somewhat the discharge end of said passageways, said discharge opening of said block being so proportioned to the exposed part of said discharge ends as to be greater than 55 one of said discharge ends and less than the combined ends, said passageways being arranged in respect to said chamber so that the oil discharging therefrom will first move tangentially across the peripheral part of the chamber, then merge 60 into a whirling central mass and finally form a single stream passing through said discharge opening and means for securing said nozzle block to said burner body.
